UNITED STATES PATENT OFFICE.

JAMES PHIPPS, OF PHILADELPHIA, PENNSYLVANIA, ASSIGNOR TO MARTIN LANDENBERGER & COMPANY, OF SAME PLACE.

DESIGN FOR TRIMMING.

Specification forming part of Design No. **6,637**, dated May 6, 1873; application filed April 15, 1873.

A.

To all whom it may concern:

Be it known that I, JAMES PHIPPS, of Philadelphia, Pennsylvania, have invented a Design for a Fringe or Border, of which the following is a specification:

The nature of my design is clearly shown by the accompanying drawing, the figures in which represent the fringe or border in different shades or colors, varying effects being thus produced without changing the arrangement of the threads.

The fringe is composed of a longitudinal flat band, *a*, crossed by a looped thread or threads, *b*, which extend beyond the said band on both

sides, and form an open scalloped edging for the fringe, longitudinal tying-threads *c c* also appearing upon the surface of the fringe and forming part of the ornamentation of the same.

Irrespective of the colors employed, I claim—

The design for a fringe or border, substantially as described, and as represented in and by the accompanying drawing.

In testimony whereof I have signed my name to this specification in the presence of two subscribing witnesses.

Witnesses: JAMES PHIPPS.

ROBERT McCONNELL,

JOHN F. TAGUE.
